FIG. 1

FIG. 2

FIG. 3

FIG. 4

FIG. 5

FIG. 6

FIG. 7

FIG. 1 is a perspective view of a combined arm rest and storage container for tape cartridges showing our new design, the broken line representation of a car seat being shown for illustrative purposes only;

FIG. 2 is a top plan view thereof on an enlarged scale;

FIG. 3 is a front elevation thereof;

FIG. 4 is a rear elevation thereof;

FIG. 5 is an elevation of the side opposite that shown in FIG. 1;

FIG. 6 is a bottom plan view thereof; and

FIG. 7 is a perspective view thereof with the cover in an open position.

The stippled areas in the figures indicate a material having a surface quality similar to leather.

We claim:

The ornamental design for a combined arm rest and storage container for tape cartridges, as shown and described.
